UNITED STATES PATENT OFFICE.

JOSEPH A. SCHNUR, OF ST. LOUIS, MISSOURI.

REFRIGERATOR.

Application filed August 20, 1924. Serial No. 733,072.

This invention relates to improvements in refrigerators and the like and more particularly to that type of refrigerators known as refrigerator counters, the primary object thereof being the provision of means whereby the shelving of the refrigerator is made to form a part of the cooling system thereof.

Another object of the invention is in making the shelving hollow so that the cold draining water from the melting ice of the ice chambers will be entrained through the shelving for cooling them and for assisting in the cooling of the food chambers in which the shelving is arranged.

15 A further object of the invention is in having the shelving form a part of the draining system of the refrigerator.

A still further object of the invention is in providing the refrigerator with vertically 20 disposed ice chambers arranged one above another and separate from each other so that the drain water from each ice chamber can be entrained in respective hollow shelvings.

Others and further objects will appear in 25 the specification and be specifically pointed out in the appended claims, reference being had to the accompanying drawings, exemplifying the invention, and in which:—

Figure 1 is a longitudinal vertical section 30 of a portion of a refrigerator counter disclosing this improvement in connection therewith.

Figure 2 is a horizontal section taken on the line II—II of Fig. 1.

35 Figure 3 is a transverse vertical section taken approximately on the line III—III of Fig. 1.

Referring by numerals to the accompanying drawings, 1 designates a refrigerator counter having a pair of vertically arranged removable ice chambers 2 and 3 each having an inclined bottom 4, the inclined bottom of the upper chamber 3 forming a top wall to the lower chamber 2 whereas the upper chamber 45 3 is provided with an inclined cover 5.

In the drawing, approximately one-half of a refrigerator counter is shown, the ice chambers 2 and 3 being arranged at one end of the counter, the chamber 2 being provided with 50 an outlet 6 in the inner wall 7 which leads from the inclined bottom 4, said outlet leading to a downwardly disposed transversely arranged discharging spout 8 which is engaged in the trough or cross-bar 9 of the lower shelving 10.

The shelving 10 is comprised of a series of longitudinal extending tubular members 11 which extend from trough 9 to the cross-member 12.

Depending from each end of the cross-members 12 is a down spout 13, each of which is engaged into one end of a respective horizontally disposed tubular member 14, each of said tubular members 14 having a longitudinally disposed dividing strip 15 which inclines downwardly from the end with which the down spout 13 engages to the opposite end thereby providing a pair of inclined passageways 16 and 17 in each of said members 14.

The discharging end 18 of each of the members 14 each communicate with a respective funnel 19 of a transversely disposed tubular member 20, said member 20 as shown in Fig. 3 being formed so as to incline downwardly from each end to the center of the drain 75 pipe 21.

Formed in the inner wall 22 of the upper arranged ice bunker 3 is a transversely disposed outlet 23 which communicates with a discharging spout 24, said spout being engaged in a trough or cross member 25, and leading from said trough are a series of tubular members 26 which incline downwardly and communicate with a tubular cross member 27, said members 25, 26 and 27, comprising the upper shelving 28. Leading from each end of the cross member 27 is a depending down spout 29, each of said spouts engaging and communicating with the cross member 12 directly above a respective down 90 spout 13.

From the above description, it is obvious that the oppositely disposed half of the refrigerator counter is comprised of similar parts such as the upper shelving 28^a, down 95 spouting 29^a and 13^a and tubular members 14^a having respective discharge ends 18^a which are inserted in respective funnels 19 of the transversely disposed tubular member 20 which leads to the drain pipe 21.

In the operation of this improved refrigerator when ice is contained in the respective ice chambers 2 and 3, the cold water from the melting ice of the upper compartment 3 will travel down the inclined bottom 4 and into the spout 24 and be discharged into the trough 25 into the upper shelving 28 from where it will drain into the longitudinal disposed tubular members 26 of said shelving into the cross member 27 to the down spouts 100 105 110 115

29 and 13 to the passageways 16 and 17 to the funnel 19 and finally discharged through the tubular member 20 and drain pipe 21.

5 The water from the melting ice contained in the ice chamber 2 will be discharged from the inclined bottom 4 through the outlet 6 and through the discharging spout 8 into the trough 9 of the shelving 10 and from said trough through the tubular members 11 from 10 where it will be discharged to the cross member 12 and down spouts 13 thereof to respective tubular members 14 to the tubular member 20 and drain pipe 21.

15 This entrainment of the cold water from the respective ice chambers and the respective shelvings 10 and 28 and draining means therefrom will not only keep the shelving cold but supply an amount of refrigeration to the food chambers 30 and 31 during its 20 travel through the tubular structures thereby deriving a maximum amount of refrigeration from the ice contained in the ice chambers and draining water therefrom.

25 The shelvings 10 and 28 are removably supported upon the cross-bars 32, whereas the tubular members 14 are supported upon the cross-bars 33 so that when it is desired to clean the tubular structure it can readily be removed.

30 **What I claim is:**

1. In a refrigerator, a pair of ice chambers arranged one above the other, each being provided with a draining outlet, a pair of hollow shelves each being in communication 35 at one end with an outlet of a respective chamber, a pair of pipes depended from the opposite end of each of said shelves, one of

said pair of pipes telescoping into said other pair of pipes, and a member having a return passageway formed therein in communication with each pipe of said last mentioned pair of pipes.

2. In a refrigerator, a pair of ice chambers arranged one above the other each being provided with a draining outlet, a pair of hollow shelves each being in communication at one end with an outlet of a respective chamber, draining means depended from the opposite end of each of said shelves and a tubular member having a return passageway 50 in communication with said draining means.

3. In a refrigerator, an ice chamber located at each end of the refrigerator each having a drain opening, a pair of hollow shelves disposed intermediate of said chambers in approximate horizontal alinement each comprising a series of spaced apart tubular members, each of said shelves being in communication at one end with a drain opening of a respective chamber, draining means depending from adjacent abutting ends of said shelves, and a member having a return passageway form therein in communication with each of said draining means.

4. In a refrigerator, an ice chamber having a drain opening, a shelf comprising a series of spaced communicating tubular members, one of said tubular members being in communication with the drain opening of said chamber, draining means leading from one of said tubular members, and a member having a return passageway formed therein in communication with said draining means.

JOSEPH A. SCHNUR.
